(57) **CLAIM**

We claim the ornamental design for a cylinder holder, as shown and described.

DESCRIPTION

FIG. 1 is a top, front, right side perspective view of a cylinder holder showing our new design;

FIG. 2 is a bottom, rear, left side perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines shown in the figures represent portions of the cylinder holder that form no part of the claimed design. In FIGS. 1-6, the cylinder holder is shown with a symbolic break in its length. The appearance of any portion of the article between the break lines forms no part of the claimed design.
